UNITED STATES PATENT OFFICE

2,490,908

EARRING

Thomas A. Kohler, Chicago, Ill.

Application May 9, 1946, Serial No. 668,600

9 Claims. (Cl. 63—14)

1

The invention relates to earrings.

One object of the invention is to provide an earring which includes members adapted to engage the inner and outer surfaces of the lower portion of the concha of the ear to securely support the earring without excessive pressure on the ear and which comprises slidably connected sections which permit the earring to be easily and quickly applied to and removed from the ear.

Another object of the invention is to provide an earring which includes sections which are connected for attachment to and removable from the ear by a slidable connection which is frictionally self-retaining to facilitate the placement of the earring on the ear and its removal therefrom.

Other objects of the invention appear in the detailed description.

The invention consists in the several features hereinafter set forth and more particularly defined by claims at the conclusion hereof.

In the drawings:

Fig. 1 is a perspective of an earring embodying the invention.

Fig. 2 is a side elevation, the portion of the ear to which the earring is applied being indicated by dotted lines.

Fig. 3 is a perspective of the section which is formed of plate metal.

Fig. 4 is a perspective of the section which is formed of wire.

Fig. 5 is a plan of the blank from which the plate metal section is formed.

The invention is exemplified in an earring which comprises a section generally designated *a*, and a section generally designated *b*, which are slidably connected and provided, respectively, with confronting members for engaging the inner and outer surfaces of the lower portion of the concha of the ear.

Section *a* is preferably formed of sheet metal and comprises a disk-like member 10 which is adapted to fit the concave inner surface of the lower portion of the concha of the ear and is concavo convex to measurably conform to said surface, and a depending integral leg 11 adapted to extend downwardly in front of the lobe of the ear.

Section *b* is formed of a single strip of wire and comprises; a loop 14 in confronting relation with the disk-like member 10 and which is adapted to engage the outer surface of the lower portion of the concha of the ear; a pair of legs 15 depending from the ends of loop 14, respectively; lower portions 16 adapted to extend under

2

the lobe of the ear; and upstanding legs or members 17 which overlap the front face of leg 11 on section *a* and are slidably secured in eyes 18 which are integral with and project forwardly from the front face of leg 11. The legs 17 are of sufficient length for sufficient sliding movement of section *b* on section *a* to permit the disk-like member 10 and loop 14 to be shifted into contact with the inner and outer surfaces of the lower portion of the concha and to be separated sufficiently for the convenient insertion of the lobe of the ear between the depending legs 15 on section *b* and leg 11 on section *a*, and to permit loop 14 and member 10 to be shifted together into the desired spaced relation for holding the earring on, and without undue pressure or pinching on the ear. One or both of the legs 17 are bent or bowed for frictional engagement with the eyes or loops 18 so that sections *a* and *b* will be frictionally self-retained in their relatively assigned positions. The upper end of one of the legs 17 is offset as at 19 to prevent the withdrawal of the leg 17 from eye 18 and to prevent complete separation of the sections.

Section *a* is formed of a single piece of metal, and eyes 18 are formed from tongues projecting from the portion of the blank which forms the depending leg 11.

An ornament 20 indicated by dotted lines in Fig. 2 of any suitable design, is attached to the front of the earring to conceal the slidable connections between the sections and is usually provided on its back with an attaching screw. In order to provide stock of sufficient thickness for the screw on the ornament for securely attaching it to the earring, the tongue forming one of the eyes 18 is extended and folded across as at 22 against the front face of leg 11. This provides a double thickness of metal stock for the screw-thread 23 by which the screw on the ornament is attached to the ornament.

Section *b* is preferably formed of a single piece of wire bent to the contour illustrated in Fig. 4. After the upstanding legs 17 have been passed through eyes 18, the upper end of one of said legs is bent as at 19 to prevent complete separation of the sections.

The disk-like member 10 which extends into the ear is provided with a hole 24 for the attachment of a hearing-aid to the earring.

When the earring is to be worn, the sections *a* and *b* are slidably spread apart so that member 10 can be inserted into the ear and in contact with the inner surface of the lower portion of the concha and the loop 14 placed under said

portion, with the lobe between legs 15 on section b and leg 11 on section a, as illustrated in Fig. 2. The dished disk-like member 10 will contact with and conform to the curved concave inner surface of the lower portion of the concha. The sections will then be pushed together until the lower portion of the concha is confined between member 10 and loop 14. The dished member 10 will seat in the lower portion of the concha and will be held seated by the loop 14. In order to secure the earring in place, it is not necessary to move member 10 and loop 14 sufficiently close together to uncomfortably pinch or grip the ear. The frictional or resilient gripping between legs 17 and eyes 18 will securely hold the sections in their assigned relative positions. In this manner, the earring may be comfortably worn. When the removal of the earring is desired, the sections are slidably spread apart, whereupon the earring can be easily removed from the ear.

The invention exemplifies an earring which is composed of sections which are slidably connected and are adapted to be held in assigned spaced relation for holding the earring on the ear without uncomfortable pressure or pinching. The frictional gripping between the sections holds them in their assigned spaced relation and securely retains the earring on the ear with any degree of pressure desired. The construction is simple and includes a plate metal section and a wire section which can be economically fabricated and the plate section is utilized for attachment of the usual ornament and the hearing aid.

The invention is not to be understood as limited to the details described, since these may be modified within the scope of the appended claims without departing from the spirit and scope of the invention.

Having thus described the invention, what I claim as new and desire to secure by Letters Patent is:

1. An earring comprising a section of substantially flat metal having a laterally extending disk-like member for engaging the inner surface of the lower portion of the concha of an ear; a second section formed of wire, including a loop for engaging the outer surface of the concha in confronting relation with the disk member, the sections extending in front of, under and back of the lobe of said ear; the second section including resilient means slidably connecting the sections for sliding said members apart to receive, and together to engage, the lower portion of the concha.

2. An earring comprising a section of flat metal having a laterally extending disk-like member for engaging the inner surface of the lower portion of the concha of an ear and an integral depending leg extending over the front of the lobe of the ear; a second section formed of wire extending under and upwardly at the back of the lobe and including a loop for engaging the outer surface of the concha in confronting relation with the disk member; and a front portion overlapping the leg; and means for slidably connecting the leg and said overlapping portion to permit separation of the disk-like member and the loop for receiving the ear between them.

3. An earring comprising a section of flat metal having a laterally extending disk-like member for engaging the inner surface of the lower portion of the concha of an ear and an integral depending leg extending over the front of the lobe of the ear and provided with means whereby an ornament may be attached thereto; a second section formed of wire extending under and upwardly at

the back of the lobe and including a loop for engaging the outer surface of the concha in confronting relation with the disk member; and a front portion overlapping the leg; and means for slidably connecting the leg and said overlapping portion to permit separation of the disk-like member and the loop for receiving the ear between them.

4. An earring comprising a section of flat metal having a laterally extending disk-like member for engaging the inner surface of the lower portion of the concha of an ear and an integral depending leg extending over the front of the lobe of the ear; a second section formed of wire and including a loop for engaging the outer surface of the lower portion of the concha in confronting relation with the disk member, a pair of wire legs depending from the loop at the back of the lobe, and a pair of upstanding portions overlapping the legs on the flat metal section; and means for slidably connecting the upstanding portions to the depending leg on the flat metal section.

5. An earring comprising a section of flat metal having a laterally extending disk-like member for engaging the inner surface of the lower portion of the concha of an ear and an integral depending leg extending over the front of the lobe of the ear; a second section formed of wire and including a loop for engaging the outer surface of the lower portion of the concha in confronting relation with the disk member, a pair of members depending from the loop, and extended to provide a pair of upstanding front members, overlapping the leg of plate-metal; and integral eyes on the plate-metal leg in which the upstanding front members are slidable.

6. An earring comprising a section of flat metal having a laterally extending disk-like member for engaging the inner surface of the lower portion of the concha of an ear and an integral depending leg extending over the front of the lobe of the ear; a second section formed of wire and including a loop for engaging the outer surface of the lower portion of the concha in confronting relation with the disk member, a pair of members depending from the loop, and extended to provide a pair of upstanding front members, overlapping the leg of plate-metal; and integral eyes on the plate-metal leg in which the upstanding front members are slidable, the leg of plate-metal having folded portions providing means for attaching an ornament to the plate-metal member.

7. An earring comprising a front section of substantially flat metal including a laterally extending member for engaging the inner surfaces of the lower portion of the concha of the ear and a depending front leg; a second section including a pair of back legs with means at their upper ends for engaging the outside of the ear in confronting relation with said laterally extending member of the front section; means for slidably connecting between the back legs to the depending leg on the front section, and spring means between the depending leg of the front section and said slidably connecting means, for retaining the sections in adjusted gripping position.

8. An earring comprising a front section of substantially flat metal including a laterally extending member for engaging the inner surfaces of the lower portion of the concha of the ear and a depending front leg; a second section of wire including a pair of back legs with a cross-connection at their upper ends for engaging the outside of the ear into confronting relation with said laterally extending member of the front section and

upward extensions in front of the ear and connected to the back legs; means for slidably connecting said upward extensions and the depending leg on the front section; and spring means between the depending leg and the upward extensions on the back legs, for retaining the sections in adjusted gripping position.

9. An earring comprising a front section of substantially flat metal including a laterally extending member of extended area for engaging 10 the inner surfaces of the lower portion of the concha of the ear and a depending front leg; a second section of wire including a pair of back legs with a cross-connection at their upper ends for engaging the outside of the ear into confront- 15 ing relation with said laterally extending member

of the front section and upward extensions in front of the ear and connected to the back legs; slideable connections between said upward extensions and the depending leg on the front section; said upward extensions being resilient for retaining the sections in adjusted gripping relation.
